UNITED STATES PATENT OFFICE

JOHN A. WESER, OF NEW YORK, N. Y.

MECHANICAL MUSICAL INSTRUMENT.

No. 923,225.

Specification of Letters Patent.

Patented June 1, 1909.

Application filed April 30, 1907. Serial No. 371,033.

To all whom it may concern:

Be it known that I, JOHN A. WESER, a citizen of the United States, residing in the borough of Manhattan, of the city of New York, in the State of New York, have invented certain new and useful Improvements in Mechanical Musical Instruments, of which the following is a specification, reference being had to the accompanying drawings, forming 10 a part hereof.

This invention relates generally to automatic pianos or other musical instruments in which power for operating the various mechanical parts of the instrument is derived 15 from feeder bellows.

It is particularly concerned with the devices by which expression is controlled, either directly or indirectly, and with the connections therefor. In some instruments 20 of this general character the feeder bellows have been operated by motors, such as an electric motor, while in some cases the feeder bellows are operated by foot power. In the present case it has been found desirable to 25 combine both the motor operated bellows and the foot power bellows, particularly as the operation of the foot power bellows, in supplement to the motor operated bellows, enables the expression to be better controlled. Furthermore, it has been found 30 advisable, in order that the desired result may be produced, to make the action of the foot power bellows to a certain extent independent of the action of the motor operated bellows, so that the function of the foot power bellows, as an expression device, can be fully realized. Moreover, while in Letters Patent of the United States No. 648,717 35 dated May 1, 1900, means are shown and 40 broadly claimed for controlling expression automatically, to a greater or less extent, in a mechanical musical instrument, improved means are now provided for the same general purpose and, as in the practical application 45 of automatic expression devices to pneumatic musical instruments of the general character referred to, particularly those in which exhaust or vacuum pressure is made use of as a motive power, there is a danger point 50 beyond which the reduction of force for pianissimo passages cannot be carried without rendering possible the complete cessation of 55 automatic playing; provision is now made for protecting the operation of the devices involved so that the reduction of force to the danger point cannot take place. All of

these desirable results and others, more or less incidental thereto, as will be pointed out hereinafter, are attained by the construction and combination of parts substantially 60 as will be described hereinafter and with reference to the accompanying drawings in which, for the purpose of illustrating and explaining the nature of the invention, the present improvements are shown as embodied in a convenient and practical structure.

In the drawings—Figure 1 is a view in front elevation, with a portion of the front of the casing removed and with various 70 parts not necessary to an understanding of the invention removed, of a mechanical piano which embodies the invention. Fig. 2 is a view in front elevation of some of the parts shown in Fig. 1, but on a larger scale. 75 Fig. 3 is a view in vertical section of the parts shown in Figs. 1 and 2 on a plane indicated by the line 3—3 of Fig. 2, looking toward the right. Fig. 4 is a similar view in section on the plane indicated by the line 4—4 of Fig. 2. 80 Figs. 5—14 are detail views of various parts to be referred to. Fig. 15 is a detail view illustrating a possible means of controlling one of the expression valves.

In the embodiment of the invention illustrated in the drawings the piano strings *a* are struck by hammers *a'* operated, under the control of suitable selective devices not shown, by hammer pneumatics *a²* actuated by exhaust or vacuum pressure transmitted 90 through suitable wind-ways, header *a³*, connecting pipe *b*, valve box *c* and wind chest *c'* from main or reservoir bellows *c²*, having a movable bellows member *c³*. Exhaust or vacuum pressure is created in the main bellows *c²* by feeder bellows *c⁴* operated, as usual, by pedal mechanism *c⁵*. All of the parts thus far referred to are constructed and operated in any usual or suitable manner and need not be further described herein.

In addition to the exhaust or vacuum pressure-creating means arranged to be operated by the performer there is also provided a motor operated exhaust or vacuum pressure-creating means represented in the present instance by a series of small or supplementary feeder bellows *d* operated through the medium of a crank shaft *d'*, pulleys *d², d³* and belt *d⁴* from an electric motor *d⁵*. The supplementary feeder bellows *d* are connected, as by a suitable wind-way *e*, with the wind chest *c'* and, through that and its con-

nections, with the hammer pneumatics a^2 and other working parts of the mechanism. At some convenient point between the motor operated bellows d and the connection to the wind chest c' , as at e' , there is provided a check valve e^2 , shown in detail in Fig. 8, and comprising, as there shown, a simple flap valve coöperating with the end of the wind-way e . This check valve opens toward the foot operated bellows. The motor operated bellows are therefore in operative connection with the rest of the mechanism only when the exhaust or vacuum pressure of the motor operated bellows is greater than that in the wind chest c' , while if the exhaust or vacuum pressure produced by the foot operated bellows is greater than that produced by the motor operated bellows the check valve e^2 immediately closes and cuts off the motor operated bellows so that the foot operated bellows shall not draw air through the motor operated bellows and so that the full effect of a strong or powerful action of the foot operated bellows in accenting certain notes or in performing fortissimo passages is unaffected.

In Letters Patent No. 648,717, above mentioned, the variation of tone, in loudness or softness, is produced by varying directly the action of the sound-producing means, one of the modified embodiments of the broad invention combining a valve with the feeder bellows so that the action of such bellows upon the playing devices is varied more or less by varying the communication of such bellows with atmospheric air. In the present case a similar provision is made, a valve f , shown in Figs. 5 and 6, being arranged to control communication between the wind-way d^8 of the bellows d and atmospheric air through an air-way f' . The valve f , as shown, is provided with a stem or link f^2 through which the position of the valve is controlled. In the embodiment of the broad invention illustrated in such Letters Patent No. 648,717, the valve which corresponds to the valve f of the present case is controlled by devices which act somewhat slowly and permit but infrequent variations. In the present case, greater or more frequent variation of the sound-producing means, as controlled by the valve f , is made possible by the devices about to be described. The valve stem or link f^2 is connected to an extension f^3 (which is made elastic in order to produce a better effect) of a lever f^4 , which is suitably pivoted and is arranged to co-operate, at its other end, with an expression cam f^5 , which is mounted upon a shaft f^6 driven through a worm gear f^7 , best shown in Fig. 3, from a counter shaft f^8 which in turn is driven by suitable means, such as a belt and pulleys f^9 , from the shaft d' , above referred to. The expression wheel or cam f^5 thus rotates slowly and, as it rotates, opens more or less the valve f and thus varies the

force of the sound-producing means and therefore the loudness or softness of the tone or sound produced. The expression cam or wheel f^5 can be readily detached from its shaft and replaced by another with greater or less variation of expression to suit or correspond to the music played.

The wheel f^5 , besides having its periphery shaped to produce variations in tone through the means already described, may also be provided with an eccentric pin f^{10} to coöperate with a lever f^{11} for the purpose of controlling, through a diaphragm valve f^{12} , of ordinary construction, the pneumatic or bellows f^{13} which in turn controls, in the usual manner, the ordinary loud or sostenuto pedal.

In order that the expression, as affected by the action of the motor operated bellows d , may also be under the control of the performer, the lever f^4 may also be provided with an arm f^{14} which is connected by a link f^{15} with a rock shaft f^{17} , the handle f^{18} of which is conveniently located below the keyboard. When greater force or louder tone is desired the handle or lever f^{18} is moved from left to right, thus raising the arm f^{14} and moving the other arm of the lever f^4 from the cam wheel f^5 and increasing the tension or rod f^2 and valve f as desired. Thus by the proper movement of the lever f^{18} the automatic expression device can be thrown out of operation and greater or less tension can be put on the valve f to vary the tone as desired.

As indicated hereinbefore the wide opening of the valve f might take place at such a time or be so long continued as to bring to a cessation the operation of the instrument. To prevent such accidental stopping of the performance there is provided for the expression devices a protecting device which acts to prevent the reduction of the motive force below such danger point, such protector or protecting device being governed in its action by the variations of the pressure, vacuum or otherwise, which directly determines the operation of working parts of the instrument, such as the hammer pneumatics. As the main bellows c^2 is directly responsive to such working pressure, the movable board c^3 is made to control the action of this protecting device. As shown in the drawings there is mounted in suitable bearings in the frame a rock shaft g , one arm g' of which has a finger g^2 which projects into the path of movement of the movable bellows member c^3 , so that when such bellows is nearly expanded to its maximum, as will be the case when the working pressure is near its minimum, it will strike the finger g^2 and rock the shaft g . An arm g^3 at the other end of the shaft g extends below the arm f^3 of the lever f^4 and when the shaft is rocked, as just described, the arm g^3 lifts the arm f^3 and closes the valve f against the weight of

the connected parts (which may be supplemented by a spring, if desired) which weight tends to open the valve h^1 . Accordingly, whenever the working pressure falls nearly to the danger point the valve h^1 will be closed, regardless of the action of the expression device, and the unintended stopping of the performance through an excessive reduction of working pressure will be prevented.

In order that the playing of the instrument may be made continuously louder or softer or varied as may be desired there is mounted in a suitable position beneath the keyboard a rock shaft h provided with a suitable handle h' and with an arm h^2 which in turn is connected by a link h^3 with a so-called vent valve h^4 disposed in a valve box h^5 and arranged to control communication between the motor bellows d and the air-way e ; the opening of the valve by admitting atmospheric pressure through the pipe h^6 , as usual, reducing the working tension and making the tone softer. The reduction of tension is not sufficient under ordinary conditions to cause the check valve e^2 to close. Under some circumstances the reduction of tension by this means might reduce the working tension below the danger point and render possible the unintended stopping of the performance. To guard against this there is provided a protector for the expression valve h^4 which, being responsive to the variations of the working tension, will close the air-way to the valve h^4 from the pipe h^6 whenever the tension approaches the danger point. As shown, a protector valve h^6 is arranged in the valve box h^5 to control the air-way through the valve h^4 and is connected to a link h^7 to an arm h^8 on the shaft g which, as before described, is rocked on its axis whenever, through an excessive reduction of tension in the bellows c^2 , the movable board c^2 thereof moves outward toward its extreme position. Such reduction of working tension and movement of the board closes the valve h^6 and prevents the reduction of tension below the danger point. The valves h^4 and h^6 , with their immediate connections, are shown in detail in Figs. 10, 11, and 12. The valve h^4 may also be controlled in operation, to vary the tone, by the music sheet itself, as illustrated in Fig. 15. In the construction there shown the music sheet i , operated in the usual manner, is provided with apertures i' , i'' , adapted to coöperate with corresponding apertures k' , k'' respectively, in the tracker board k . The apertures k' and k'' communicate respectively, through tubes k^3 and k^4 , with the opposite exhaust chambers l' and l'' of a double pneumatic l . The two movable boards p and p' of this pneumatic coöperate with buttons t' and t'' on the rod h^8 . If a perforation on one side of the music sheet, as i' , registers with the corresponding aperture k' in

the tracker board k , the corresponding pneumatic, as p , is collapsed and the rod h^8 is shifted to open or close the valve h^4 as the case may be. As the valve h^4 is a slide valve its easy movement is not affected by variations in bellows pressure and it remains in the position in which it is left until it is again moved in the manner described.

For convenience in construction and in assembling the parts of the instrument, various portions, such as the valve box e and the header a^2 , or the wind box e' and the valve box e' are connected by tubes, as b and e respectively. These tubes must be tightly packed to prevent leakage and they should also be readily capable of longitudinal movement for convenience in assembling the parts. Ordinarily the packing is effected by a leather lining for the holes through which the tubes are extended, but such lining dries out and permits more or less leakage. This difficulty is overcome in the present case, as illustrated in Figs. 13 and 14, by providing at each joint between the tube b and the wall of the wind box or wind trunk, as the case may be, a soft rubber gasket b' , which fits closely about the tube and is clamped by the wall b^2 , b^3 of the wind box or trunk and a washer b^4 held by screws b^5 to the wall so that the gasket can be compressed more or less. The openings through the wall and through the washer are preferably made somewhat larger than the diameter of the pipe so that when the gasket is compressed it will expand into the space between the pipe and the wall or washer and thereby make a tight joint. This joint permits the tube to be moved endwise as may be required and, if at any time the joint leaks, it can readily be made tight by setting up the screws to compress the gasket somewhat more.

The piano illustrated in the drawings is shown as having a single foot operated bellows, but it will be obvious that the well-known arrangement of loud and soft bellows might be provided for.

It will also be understood that various other changes in details of construction and arrangement can be made according to the requirements of various instruments and that the invention, therefore, is not to be restricted to the precise construction shown and described herein.

I claim as my invention:

1. In a mechanical musical instrument, the combination of playing devices, foot operated bellows in operative relation therewith and independent motor operated bellows also in operative relation therewith, whereby notes may be accented by the foot operated bellows, while the instrument is operated by the motor operated bellows.

2. In a mechanical instrument, the combination of playing devices, foot operated bellows in operative relation therewith, inde-

- pendent motor bellows also in operative relation therewith, and means to cut off communication between the foot operated bellows and the motor operated bellows when the working force of the former exceeds that of the latter.
3. In a mechanical musical instrument, the combination of playing devices, foot operated bellows in operative relation therewith, independent motor operated bellows also in operative relation therewith, and a check valve interposed between the motor operated bellows and the playing devices and opening toward the motor operated bellows.
4. In a mechanical musical instrument, the combination of playing devices, a wind chest in operative relation therewith, foot operated bellows connected to the wind chest and independent motor operated bellows also connected to the wind chest, whereby notes may be accented by the foot operated bellows, while the instrument is operated by the motor operated bellows.
5. In a mechanical musical instrument, the combination of playing devices, a wind chest in operative relation therewith, foot operated bellows connected to the wind chest, independent motor operated bellows also connected to the wind chest and means to cut off communication between the wind chest and the motor operated bellows when the working force of the foot operated bellows exceeds that of the latter.
6. In a mechanical musical instrument, the combination of playing devices, a wind chest in operative relation therewith, foot operated bellows connected to the wind chest, independent motor operated bellows also connected to the wind chest, and a check valve interposed between the motor operated bellows and the wind chest and opening toward the motor operated bellows.
7. In a mechanical musical instrument, the combination of playing devices, bellows in operative relation therewith, means for varying the tension produced by the bellows and independent means controlled by the tension produced by the bellows to prevent the reduction of the tension produced by the bellows below a predetermined minimum.
8. In a mechanical musical instrument, the combination of playing devices, bellows in operative relation therewith, a valve to control the tension produced by said bellows, expression devices to control said valve and independent means to act upon said valve and prevent the reduction of the tension produced by the bellows below a predetermined minimum.
9. In a mechanical musical instrument, the combination of playing devices, bellows and connections including a device moving with the variations in the tension produced by the bellows, means for varying the tension produced by the bellows, and independent means controlled by said last named device to prevent reduction of the tension produced by the bellows below a predetermined minimum.
10. In a mechanical musical instrument, the combination of playing devices, main bellows in operative relation therewith, feeder bellows connected to the main bellows, means for varying the tension produced by the feeder bellows and independent means controlled by the movement of the main bellows to prevent the reduction of the tension produced by the feeder bellows below a predetermined minimum.
11. In a mechanical musical instrument, the combination of playing devices, main bellows in operative relation therewith, feeder bellows connected to the main bellows, a valve regulating the admission of atmospheric air to the connection between the feeder bellows and the main bellows to control the tension produced by said feeder bellows, expression devices to control said valve and means actuated by the main bellows to control the valve independently of the expression devices.
12. In a mechanical musical instrument, the combination of playing devices, main bellows in operative relation therewith, feeder bellows connected to the main bellows, a valve regulating the admission of atmospheric air to the connection between the feeder bellows and the main bellows to control the tension produced by the feeder bellows, expression devices to control said valve, and a rock shaft having an arm in the path of movement of the movable member of the main bellows and connections from said rock shaft to said valve to control the same independently of the expression devices.
13. In a mechanical musical instrument, the combination of playing devices, bellows in operative relation therewith, a valve to control the tension produced by said bellows and a rotating cam disk and intermediate devices to act upon said valve to vary the tension produced by the bellows.
14. In a mechanical musical instrument, the combination of playing devices, bellows in operative relation therewith, a valve to control the tension produced by said bellows, a rotating cam disk and intermediate devices to act upon said valve to vary the tension produced by the bellows, and means controlled by the tension produced by the bellows to prevent the reduction of the tension produced by the bellows below a predetermined minimum.
15. In a mechanical musical instrument, the combination of playing devices, bellows in operative relation therewith, a valve to

control the tension produced by said bellows, a rotating cam disk and intermediate devices to act upon said valve to vary the tension produced by the bellows, and means controlled by the tension produced by the bellows to act upon said valve independently of the cam disk.

16. In a mechanical musical instrument, the combination of playing devices, bellows in operative relation therewith, a valve to control the tension produced by said bellows, a cam disk and intermediate devices to act upon said valve to vary the tension produced by the bellows and hand operated devices to act upon the valve independently of the cam disk.

17. In a mechanical musical instrument, the combination of playing devices, bellows in operative relation therewith, a valve to control the tension produced by said bellows, a lever connected at one end with said valve and a rotating cam disk acting upon said lever.

18. In a mechanical musical instrument, the combination of playing devices, bellows in operative relation therewith, a valve to control the tension produced by said bellows, a lever having an elastic arm connected to said valve and a rotating cam disk acting upon said lever.

19. In a mechanical musical instrument, the combination of playing devices, bellows in operative relation therewith, a valve to control the tension produced by said bellows, a cam disk and intermediate devices to act upon said valve to vary the tension produced by the bellows, means controlled by the tension produced by the bellows to act upon said valve independently of the cam disk, and hand operated devices to act upon said valve independently of said cam disk and of said means.

20. In a mechanical musical instrument, the combination of playing devices, bellows in operative relation therewith, hand operated means to regulate the tension produced by the bellows, and independent means controlled by the tension produced by the bellows to prevent the reduction of the tension produced by the bellows below a predetermined minimum.

21. In a mechanical musical instrument, the combination of playing devices, bellows and connections including a device moving with variation in the tension produced by the bellows, hand operated means to regulate the tension produced by the bellows, and independent means controlled by said last named device to prevent the reduction of the tension produced by the bellows below a predetermined minimum.

22. In a mechanical musical instrument, the combination of playing devices, main bellows in operative relation therewith, feeder

bellows connected to the main bellows, hand operated means to regulate the tension produced by the feeder bellows, and independent means controlled by the main bellows to prevent the reduction of the tension produced by the bellows below a predetermined minimum.

23. In a mechanical musical instrument, the combination of playing devices, main bellows in operative relation therewith, feeder bellows connected to the main bellows, a valve to regulate the tension produced by the feeder bellows, a second valve to control the air-way through the first valve, and connections whereby the second valve is controlled from the main bellows.

24. In a mechanical musical instrument, the combination of playing devices, bellows in operative relation therewith, a valve to control the tension produced by said bellows, motor operated expression devices to act upon said valve, and independent devices to hold said valve continuously closed.

25. In a mechanical musical instrument, the combination of playing devices, a wind-chest, main or reservoir bellows, foot operated feeder bellows in operative relation with the main or reservoir bellows, and independent motor operated bellows also in operative relation with said main or reservoir bellows.

26. In a mechanical musical instrument, the combination of playing devices, a wind-chest, main or reservoir bellows, foot operated feeder bellows in operative relation with the main or reservoir bellows, independent motor operated bellows also in operative relation with said main or reservoir bellows, and means to cut off communication between the foot operated bellows and the motor operated bellows when the working force of the former exceeds that of the latter.

27. In a mechanical musical instrument, the combination of playing devices, a wind-chest, main or reservoir bellows, foot operated feeder bellows in operative relation with the main or reservoir bellows, independent motor operated bellows also in operative relation with said main or reservoir bellows, and a check valve interposed between the motor operated bellows and the playing devices and opening toward the motor operated bellows.

28. In a mechanical musical instrument, the combination of playing devices, a wind-chest, main or reservoir bellows, foot operated feeder bellows in operative relation with the main or reservoir bellows, independent motor operated bellows also in operative relation with said main or reservoir bellows, and mechanical devices for controlling the tension produced by the motor operated bellows.

29. In a mechanical musical instrument, the combination of playing devices, a wind-

chest, main or reservoir bellows, foot operated feeder bellows in operative relation with the main or reservoir bellows, independent motor operated bellows also in operative relation with said main or reservoir bellows, and independent means to prevent the reduction of tension in either of said bellows below a predetermined minimum.

This specification signed and witnessed this 27th day of April, A. D., 1907.

JOHN A. WESER.
